Term of patent 7 years

(Cl. D90—20)

Fig. 1

*Fig. 2**Fig. 3*Fig. 1 is a perspective view of a tire embodying our new design, it being understood that the full line portion is repeated throughout the circumference of the tire shown by means of broken lines;

Fig. 2 is an enlarged fragmentary plan view of the full line portion of Fig. 1, and

Fig. 3 is a sectional view taken substantially on the plane indicated by line III-III of Fig. 2.

The dominant feature of our design resides in the portions shown in full lines in the drawings.

We claim:

The ornamental design for a pneumatic tire, substantially as shown and described.
